ABSTRACT: A landing-float pad for parachutists which is worn deflated and folded as an overshoe on the right-foot boot before and when jumping and is inflated before landing. Made of fabric and rubber, it is held in folded condition by magnets. It is inflated by air released from a compressed-air container by pressure of the left foot. The pad serves as a cushion when falling to the ground and as a float when falling in water.

FIG. 1

FIG. 2

FIG. 3

FIG. 4

INVENTOR.
HENRY DOHERTY

**EQUIPMENT TO PREVENT INJURY DURING A
PARACHUTIST'S LANDING**

This invention relates to the impact of landing by a parachutist and particularly to a landing float pad which is worn on the right-foot boot of a parachutist.

Parachutists of ten suffer severe shock, dislocations, sprains and broken bones on landing. Sometimes they are killed by the violent force of their landing or drowned in water. Inadvertently, they must land on sharp rocks, in trees or in deep or turbulent water.

It is a primary object of this invention to cushion the severe shock of impact when a parachutist lands.

It is a further object of this invention to protect the parachutist from sharp rocks or the branches of trees in the event of landing in bad terrain or in woods.

Another object of this invention is to provide an aquatic life saver, keeping the parachutist afloat if he should land in deep water.

Briefly, this invention is a Parachutist Landing-Float Pad which is worn before and at the time of jumping in a folded position and by means of an overshoe on the right-foot boot of a parachutist. It is inflated to cushion the impact of landing at any time after jumping and before landing by releasing compressed air from a container by pressing down on it by the free left foot. The pad is inflated to a trapezohedral-shaped cushion providing a foot rest for the left foot, which is free to kick the pad off from its attachment to the right-foot boot after landing. The inflated pad also can serve as an aquatic life saver, having side straps that the parachutist can hold on to if he should land in water. If the pad has not been punctured or otherwise damaged in landing, it can be used over again by replacing the spent compressed-air container with a fresh one.

It is intended that the pad, inflated to $\frac{1}{2}$ pounds pressure to cushion the average weight of parachutists, will depress vertically and expand laterally enough under the impact of landing so that the parachutist's feet could lightly touch the ground, preventing rebound while absorbing 90 percent of the shock of landing.

In order to facilitate a more complete understanding of the invention, reference is had to the accompanying drawings which illustrate several embodiments of the invention diagrammatically by way of example, and with illustrative rather than any limitative intent. In the drawing:

FIG. 1 is a drawing of the landing-float pad showing it inflated as it would be at the time of landing.

FIG. 2 is a drawing of the landing-float pad before inflation, folded and worn by means of its overshoe on the right-foot boot of a parachutist.

FIG. 3 is a drawing of the deflated and folded landing-float pad showing the compressed-air container separated from the air inlet stem.

FIG. 4 is a drawing of the bottomside of the deflated landing-float pad showing the first step in folding it and the location of magnetized holding plates.

Referring to the drawings, wherein like elements are denoted by identical reference numerals, and first to FIG. 1, the landing-float pad has a six-sided housing 10, tapered toward front and rear. The pad is made of rubber, or with a tough, air-sealed fabric top and bottom with expandable rubber sides, as light in weight as consistent with sufficient strength and elasticity to withstand the impact of a heavy landing without rupturing. It is 21 inches from front to rear edges, 18 inches wide at toe front, 14 inches wide at heel rear, and 6 inches high.

A rubber overshoe 11, similar to a rubber worn on a conventional shoe in wet weather, is vulcanized to the pad slightly right offcenter. The overshoe is for the right foot and is made in several sizes in order to fit varying foot sizes snugly, but not too tightly that it cannot be readily kicked off by the free left foot. The overshoe has a lining of cotton so that it will not cling excessively and it has a hard rubber spur 12 above the heel on which the left foot can exert sharp downward pressure

to shed the overshoe with the landing-float pad from the right-foot boot.

Alongside the overshoe 11, to its left, is a roughened, reinforced area 13 for the left foot of the parachutist to be placed in a free position at time of landing. When the pad is worn folded around the overshoe 11 before inflation, as shown in FIGS. 2 and 3, this area 13 acts as a sole to the overshoe 11 on the right-foot boot.

Long nylon straps 14 are attached to the right and left sides of the landing-float pad, one strap on each side. The strap on the left side is shown in FIG. 1. In the event of landing in deep or rough water, the parachutist can cling to the floating pad by these straps to save his life from drowning.

The landing-float pad is inflated by means of a threaded steel stem 15 imbedded in front-top of the pad and a compressed-air container 16 screwed to this stem, shown variously in FIGS. 1, 2 and 3. When the landing-float pad is folded, as shown in FIGS. 2 and 3, the compressed-air container 16 attached to the air inlet stem 15 is located forward of the arch of the right foot. The stem and container 16 are shown separated in FIG. 3. The stem 15, similar to that on a bicycle tire, but without inside threads and a valve, is mounted on the corners of a square spring plate and houses a hollow steel point independently mounted on the rigid bottom center of the spring plate to puncture the seal of the compressed-air container, releasing the air into the pad instantly. The steel point is made to puncture the seal when the parachutist presses down on the 3-inch-wide flat top of the container with his free left foot.

Shown in FIG. 1, two magnetized steel blocks 17 are mates to two nonmagnetized steel blocks 18. The two magnetized steel blocks 17 are shown imbedded in the left side edge of the pad and the two nonmagnetized blocks 18 are shown imbedded, one on the toe front of the overshoe 11 and the other on the heel rear of the overshoe. Attracted together, they hold the landing-float pad folded around the overshoe before the pad's inflation. The magnetized steel blocks are charged to that degree to relinquish their hold when the air pressure in the pad reaches less than 1 pound, or approximately 50 percent less than the full pressure attained in the pad.

In FIGS. 2 and 3 the two magnetized steel blocks 17 are shown in their positions held by attraction to the nonmagnetized steel blocks 18 on the folded pad.

The deflated landing-float pad is folded around the overshoe 11 before the overshoe is slipped on to the parachutist's right-foot boot. The method of folding the deflated landing-float pad around the overshoe, shown completed in FIGS. 2 and 3, is first to turn inward and bottomward the extensions beyond the toe and heel of the overshoe, as shown in FIG. 4. These folds are each held in place by two magnetized steel blocks 19, attached to both the toe and heel inward folded edges, making contact with nonmagnetized blocks 20, shown in FIG. 4. Next, the deflated pad is wrapped from the left underneath the overshoe so that the reinforced area for the left-foot boot at time of landing becomes the sole for the right-foot boot. The compressed-air container 16 screwed to its air inlet stem 15 becomes located forward of the arch of the overshoe and the magnetized blocks 17 meet the nonmagnetized blocks 18, thereby holding the pad in its folded position.

The invention is susceptible of modifications and changes in detail. For example, the landing-float pad could be made larger as a boon to parachutists in the armed forces, carrying the added weight of fighting equipment. By using compressed-air containers holding different pressures for different weights of parachutists, the pad could be inflated to hold more or less than $1\frac{1}{2}$ pounds of air pressure. It could be inflated with hydrogen or helium to make it lighter. Also, it could be adapted to skids holding supplies and equipment, having a timing device to release the compressed air into the landing-float pad after the skid has been jettisoned from the cargo plane.

I wish it to be understood that I do not desire to be limited to the exact details of construction, design and operation shown

and described herein, as modifications within the scope of the appended claims which do not involve a departure from the spirit of the invention nor a sacrifice of any of the advantages thereof, may occur to workers in this field.

I claim:

1. A landing-float pad for a parachutist which is carried in a deflated prejump position folded around an overshoe worn on the right-foot boot and can be inflated after the parachutist has jumped and before landing.

2. A landing-float pad for a parachutist which is carried in a deflated prejump position folded around an overshoe worn on the right-foot boot and can be inflated after the parachutist has jumped and before landing, said pad having magnetized steel blocks attracted to nonmagnetized blocks, thereby holding the pad in its folded prejump position around said overshoe worn on the right-foot boot.

3. A landing-float pad for a parachutist which is carried in a deflated prejump position folded around an overshoe worn on the right-foot boot and can be inflated after the parachutist has jumped and before landing, said pad having an assembly of an air inlet stem with a hollow point to pierce the seal of a compressed-air container by pressing down on said container by the left foot in order to inflate the said pad before landing.

4. A landing-float pad for a parachutist which is carried in a deflated prejump position folded around an overshoe worn on the right-foot boot and can be inflated after the parachutist has jumped and before landing, said pad having a roughened, reinforced area serving as a placement for the left foot at the time of landing and said area also serving as the sole for the right-foot boot when the pad is in its deflated and folded prejump position.

5. A landing-float pad for a parachutist which is carried in a deflated prejump position folded around an overshoe worn on the right-foot boot and can be inflated after the parachutist has jumped and before landing, said pad having on its said overshoe a large, hard spur above the heel by pressing down on which the left foot can shed the pad from the right-foot boot.

6. A landing-float pad for a parachutist which is carried in a deflated prejump position folded around an overshoe worn on the right-foot boot and can be inflated after the parachutist has jumped and before landing, said pad having side straps to be clung to by a parachutist after said pad's inflation and if he should land in deep water.

UNITED STATES PATENT OFFICE
CERTIFICATE OF CORRECTION

Patent No. 3,601,829 Dated August 31, 1971

Inventor(s) Henry Doherty

It is certified that error appears in the above-identified patent and that said Letters Patent are hereby corrected as shown below:

Column 1, line 35, "inflated to 1/2 pounds pressure" should read -- inflated to 1 1/2 pounds pressure --.

Signed and sealed this 25th day of July 1972.
